(57) **CLAIM**

The ornamental design for a handle for a back scrubbing device, as shown and described.

DESCRIPTION

FIG. 1 is a perspective view of a handle for a back scrubbing device showing my new design in use, with a human figure and scrubbing device shown in broken lines for illustrative purposes only and forming no part of the claimed design; FIG. 2 is an enlarged perspective view of the handle of FIG. 1;

FIG. 3 is a top plan view of FIG. 2;

FIG. 4 is a bottom plan view of FIG. 2;

FIG. 5 is a side elevational view of FIG. 2;

FIG. 6 is the opposite elevational side view of FIG. 2;

FIG. 7 is an enlarged left end view of FIG. 2; and,

FIG. 8 is an elevational view of the opposite end of FIG. 7.
